Patented Nov. 8, 1898.

J. W. ANDREWS & W. E. RAGAN.

KITCHEN CABINET.

(Application filed Oct. 17, 1898.)

UNITED STATES PATENT OFFICE.

JAMES W. ANDREWS AND WILLIAM E. RAGAN, OF MELBOURNE, ARKANSAS.

DESIGN FOR A KITCHEN-CABINET.

SPECIFICATION forming part of Design No. 29,637, dated November 8, 1898.

Application filed October 17, 1898. Serial No. 693,828. Term of patent 7 years.

To all whom it may concern:

Be it known that we, JAMES W. ANDREWS and WILLIAM E. RAGAN, citizens of the United States, residing at Melbourne, in the county 5 of Izard and State of Arkansas, have invented a new and useful Design for a Kitchen-Cabinet, of which the following is a specification.

This invention relates to a new and original design for a kitchen-cabinet; and it has for its object to provide a design of this character that shall be both useful and ornamental.

The leading feature of the design resides in an oblong rectangular bin-body having an approximately square horizontal elevation 5 projecting above the plane of the flat top thereof and arranged at a central point between its ends and an upright cupboard extension projected upward from the rear side of the body and provided with a rectangular box portion overhanging the squared elevation at the top of the bin-body, said upright cupboard extension being further provided with side pieces of a downwardly-tapering width and having compoundly-curved front edges extending from the rear side of the body to the front of said overhanging box portion.

The minor features of the design are the body, having a pair of front drawers arranged in the vertical plane of said squared elevation at the top, horizontal cleat projections at the ends of the body near the top and extending transversely from side to side of the body, and the box portion of the cupboard extension, having a pair of front doors, each provided with a rectangular perforated panel.

In the drawings, Figure 1 is a perspective view of the kitchen-cabinet embodying the herein-described design. Fig. 2 is a front elevation thereof, and Fig. 3 is a side view of the same.

Referring to the accompanying drawings, the numeral 1 designates an oblong rectangular bin-body provided at its bottom corners with short leg projections 2, having squared ends 3 next to the bin-body and annularly scalloped below said squared ends 3. The

oblong rectangular bin-body 1 is further provided at its ends near the top with transverse cleat projections 4, extending the full width thereof, and on its upper side is provided with 50 an approximately square horizontal elevation 5. The horizontal elevation 5 of the bin-body projects above the plane of the flat top thereof and overlaps the front strips 6, located at the upper front edge of the bin-body, at opposite 55 sides of the vertical plane of the said elevation 5. The bin-body 1 is also provided with a pair of front drawers 7, arranged in the vertical plane of the squared elevation 5, and with an upright cupboard extension 8. This 60 cupboard extension 8 projects upward from the rear side of the bin-body, directly in rear of the elevation 5, and is provided at its upper end with a box portion 9, having a forward projection and overhanging the squared 65 elevation 5 at the top of the bin-body. The box portion 9 of the cupboard extension is provided at its front side with rectangular doors 10, each provided with a rectangular perforated panel 11, and below said box portion 70 the cupboard extension is provided with a plain rectangular panel 12, lying in a vertical plane between the side pieces 13 of the extension. The said side pieces 13 of the extension are of a downwardly-tapering width 75 and are provided with compoundly-curved front edges 14, extending from the rear side of the body to the front of the overhanging box portion 9.

What we claim, and desire to secure by Letters Patent, is—

The design for a kitchen-cabinet herein shown and described.

In testimony that we claim the foregoing as our own we have hereto affixed our signatures 85 in the presence of two witnesses.

JAMES W. ANDREWS.
WILLIAM E. RAGAN.
